UNITED STATES PATENT OFFICE.

ROBERT CHARLES GREEN, OF WINCHESTER, ENGLAND.

HYDRAULIC RAM FOR RAISING WATER.

1,395,343.

Specification of Letters Patent.

Patented Nov. 1, 1921.

Application filed October 14, 1918. Serial No. 258,070.

(GRANTED UNDER THE PROVISIONS OF THE ACT OF MARCH 3, 1921, 41 STAT. L., 1313.)

To all whom it may concern:

Be it known that I, ROBERT CHARLES GREEN, a subject of the King of Great Britain and Ireland, a resident of Winchester, England, and whose post-office address is Vulcan Iron Works, Winchester, England, have invented certain new and useful Improvements in Hydraulic Rams for Raising Water, (for which I have filed an application 10 in Great Britain Oct. 11, 1917, Patent 119,701, sealed Jan. 22, 1919,) of which the following is a specification.

This invention for improvements in hydraulic rams for raising water has for its object to enable any desired number of pulse or waste valves to be readily fitted to the injection drive or feed pipe so that the capacity 15 of the ram may be increased and the bed of the ram or valve box be constructed in such a manner that shall prevent it from "breathing" or "expanding" when subjected to the force of the pulsations of the water and consists in forming the bed of the ram or valve box with collocated tubular valve-carrying 20 sections or valve bodies adapted to be readily assembled in any required number according to the desired capacity of the ram. Each tubular section has a through way 25 and is capable of being joined at the ends of the through way to the injection pipe and to another similar tubular section or to a cover plate.

The pulse or waste valves are fitted on the tubular sections and the air chambers or outlet pipes are also fitted on tubular sections 30 similar to the valve carrying sections.

The water enters the air chamber or vessel through a suitable delivery valve fixed inside the same.

40 This form of ram is specially suited for irrigation work or for any situation where it is desired to elevate a large body of water.

In the accompanying sheet of illustrative drawings—

45 Figures 1 and 2 are side elevation and plan respectively of a hydraulic ram constructed according to this invention.

Fig. 3 is a transverse section showing the connection between the air chamber and 50 valve bed and

Fig. 4 is a vertical detail section through one of the waste or pulse valves.

In the form of construction illustrated the bed of the ram or valve box is built up of

two series of tubular sections *a* terminated 55 by curved end sections *a*¹ and joined to the injection or drive pipe by a bifurcated end section *b* thereon formed with joining flanges *c*.

As shown the tubular sections *a* are of cylindrical form being circular in cross section and the cross sectional area of the through ways of the sections *a* is equal to that of the branches *b*¹ of the bifurcated end section *b* of the drive pipe. Flanges *c*¹ are provided 60 on the ends of the sections *a* through which bolts not shown are passed to secure them together, the terminal sections *a*¹, ram bed or valve box sections *a* and drive pipe section *b* being also provided with integral base 65 flanges or feet *a*², *b*².

In assembling the sections *a* two of them are secured to the branches *b*¹ of the bifurcated end section *b* of the injection pipe and then as many sections as desired are connected on in sequence, the ends of the two last straight sections *a* being either connected to terminal curved sections *a*¹ or closed off by cover plates.

The pulse or waste valves *d* are fitted to 80 flanged openings *e* on the tops of the sections *a*, *a*¹.

These valves are preferably of the duplex type with superposed inclined annular seatings *d*¹ and for each seating *d*¹ have an annular rubber ring *e*¹ that is adapted to close orifices *d*² in the inclined annular seating, through which the waste water passes when the valves are open.

In the form of ram shown a bifurcated 90 pipe *f* flanged at its ends connects two side-by-side sections *a* with the air chamber or vessel *g* to which the water is admitted by a delivery valve consisting of a flat perforated metal plate or grid *h* covered with a rubber disk *h*¹ and opening against a curved metal guard *h*². Any other suitable form of valve may be employed, or for extra large rams air vessels *g* and delivery valves may be fitted to each row of tubular sections and 95 connected together with a common delivery main.

I claim:—

1. In a hydraulic ram, a bed comprising a series of separable tubular sections detachably connected together and arranged end to end, each of said sections, excepting one, being provided with waste valves, the other 100

section being connected to the air chamber vessel.

2. In a hydraulic ram, a bed comprising two parallel series of tubular sections, said sections being detachably connected together and arranged end to end, and a drive pipe having branches each connected to one end section of one of the series.

3. A hydraulic ram comprising a series of

tubular bed sections arranged and connected together end to end, a drive pipe connected to one end of said series, a closure for the opposite end of said series, and an air chamber vessel connected to an intermediate section of said series.

In testimony whereof I have affixed my signature.

ROBERT CHARLES GREEN.
